CLAIM

The ornamental design for a tackle box, as shown and described.

DESCRIPTION

FIG. 1 is a top, front, left side perspective view of a tackle box showing my new design;

FIG. 2 is another top, front and left side perspective view thereof, showing the front cover in an open position;

FIG. 3 is a perspective view thereof, showing the covers in open positions, the tray in an exploded position and the lower drawer partially open;

FIG. 4 is a left side elevational view of FIG. 1;

FIG. 5 is a top plan view of FIG. 1;

FIG. 6 is a front elevational view of FIG. 1;

FIG. 7 is a right side elevational view of FIG. 1;

FIG. 8 is a rear elevational view of FIG. 1; and

FIG. 9 is a bottom plan view of FIG. 1.
